(57) **CLAIM**

The ornamental design for an ear plug as shown and described.

DESCRIPTION

FIG. 1 is a top front perspective view of an ear plug showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom rear perspective view thereof.

The broken lines in the drawings indicate portions of the ear plug that form no part of the claimed design.

1 Claim, 8 Drawing Sheets---
